UNITED STATES PATENT OFFICE.

WILLIAM L. CHESSROWN, OF EATON, COLORADO.

SIDE-DUMPING BODY FOR VEHICLES.

SPECIFICATION forming part of Letters Patent No. 726,638, dated April 28, 1903.

Application filed August 27, 1902. Serial No. 121,204. (No model.)

To all whom it may concern:

Be it known that I, WILLIAM L. CHESSROWN, a citizen of the United States, and a resident of Eaton, in the county of Weld and State of Colorado, have invented a new and Improved 5 Side-Dumping Body for Vehicles, of which the following is a full, clear, and exact description.

My invention relates to an improvement in 10 the body or rack construction of vehicles; and the purpose of the invention is to provide a side dump wherein the dumping will be automatically accomplished the moment that sundry supports beneath the body or rack are 15 withdrawn, which withdrawal at the dumping side of the body or rack is accomplished by a single movement of a single lever, and, further, to so construct the rack or body that as the rack or body is restored to its normal 20 position the side gate opened for dumping will be automatically closed.

Another purpose of the invention is to provide a construction of a side-dumping body or rack which will be simple, durable, economic, and practical, automatic, and capable 25 of being used on any wagon-gear, which construction of body or rack is especially adapted for hauling sugar-beets, but which may be adapted for all purposes of a farm and upon 30 any vehicle wherein material is to be hauled and dumped, including railroad-cars.

The invention consists in the novel construction and combination of the several parts, as will be hereinafter fully set forth, 35 and pointed out in the claims.

Reference is to be had to the accompanying drawings, forming a part of this specification, in which similar characters of reference indicate corresponding parts in all the figures. 40 Figure 1 is a side elevation of the vehicle body or rack having the improvement applied, the carrying-section being in normal position. Fig. 2 is an end view of the vehicle body or rack, the carrying-section being also shown

45 in normal position. Fig. 3 is a sectional end elevation of the body or rack, showing the carrying-section in dumping position. Fig. 4 is a transverse section of the body or rack and the carrying-section in dumping position, 50 the section being taken practically on the line 4 4 of Fig. 1. Fig. 5 is a longitudinal section through a side of the base portion of the body

or rack, showing the construction of the means for lowering the supporting-standards of the rocking section of the body or rack, the section being taken practically on the line 5 5 of Fig. 3. Fig. 6 is an enlarged side elevation of the lever-controlled means for operating the side gates of the carrying-section. Fig. 7 is a detail sectional view showing the application of the dumping-lever to a side gate of the carrying-section of the body or rack, the said section being practically on the line 7 7 of Fig. 6. Fig. 8 is a vertical section taken substantially on the line 8 8 of Fig. 2, and 65 Fig. 9 is a detail perspective view of one of the bearing-blocks for the carrying-section of the body or rack.

The device consists, primarily, of a base-section A and a carrying-section B. The base-section consists of pairs of longitudinal side beams 10, connected at their bottom portions at suitable intervals apart by cross-bars 11. Transverse supporting-beams 12 are made to rest on the side beams 10, the transverse 75 beams 12 being of any suitable dimensions, and the side beams 10 are attached to the bottom cross-bars 11 through the medium of rods 13 in the form of clips.

At the central portion of each transverse 80 beam 12 a bearing-block 14 is supported, the said bearing-blocks being provided with longitudinal channels 15 in their under surfaces, so that the said bearing-blocks may straddle the transverse beams 12. Clips 16 are employed to hold the bearing-blocks on the transverse beams 12, the upper portions 17 of which clips are bifurcated, so that the upper portions of the clips may pass over the bearing-blocks at each side of their centers, 90 as is shown in Figs. 2, 3, and 4. Each bearing-block 14 at its upper central portion is provided with a trunnion 18, which trunnions extend in horizontal alignment from the side portions of the blocks, as is best shown in 95 Fig. 9.

In the spaces between the longitudinal side beams 10 of the base-section A supporting-bars 19 are pivoted at their lower ends, as is best shown in Fig. 5. These supporting-bars 100 are adapted to assume the inclined position shown in Fig. 5 or the perpendicular position shown in Fig. 1. The supporting bars or standards 19 at each side of the base-section

A are connected by a link 20, and at one end of each link one end of a spring 21 is secured, and the opposite ends of the said springs are attached to either one or the other of the 5 pair of longitudinal side beams 10. At the opposite end of each link 20 a lever 22 is pivotally attached, and the lower ends of these levers are suitably fulcrumed upon projecting arms 23 from an end of the base-section 10 A, as is illustrated in Figs. 1 and 5.

The carrying-section B of the body or rack may be of any suitable size, and consists of end sections 24, a bottom section 26, and side sections 25, which are hinged to the bottom 15 section, as is shown in Figs. 3 and 4. These side sections 25 constitute side gates for the said carrying-section B, and when dropped down flush with the bottom 26 permit the contents of the carrying-section to pass out 20 at the open side when the said carrying-section is inclined in direction of such side or is brought to the dumping position. (Illustrated in Figs. 3 and 4.)

Transverse beams 27 are arranged, preferably in pairs, at the under surface of the bottom 26, as is shown in Fig. 1, a pair of such transverse beams 27 being also at each end of the said carrying-section B. At the side portion of each end section 24, at the outer 25 faces of said sections, slats or plates 28 are secured and recessed in such manner as to provide chambers 29 (shown in Fig. 8) between the said slats or plates and the end sections 24, in which chambers 29 pulleys 30 30 are mounted to turn, and the end sections or plates 29 preferably extend down below the bottom 26 of the carrying-section, as is illustrated in the drawings.

At the central portion of each transverse 40 beam 27 of the carrying-section B of the vehicle body or rack a block 31 is secured, and these blocks are preferably slotted or have channels produced in their upper portions, whereby they may straddle the transverse 45 beams 27, and each block 31 is provided with a suitable opening to receive a trunnion 18 of a bearing-block 14. Through this connection between the bearing-blocks 14 and the blocks 31 of the carrying-section the carrying-section 50 is centrally and pivotally mounted upon the base-section A.

Suitable braces 32 are attached to the downwardly-projecting portions of the plates or laths 28 and to the bottom 26 of the carrying- 55 section. Side braces 33 are also employed, which side braces are attached to the bottom portion of the base-section A and are connected with the inner blocks 31 of the under set of blocks, as is shown in Fig. 1, turn- 60 buckles 34 being located between the points of attachment with the base-section A and the attachment of said braces with the carrying-section, so that these braces need in no manner interfere with the dumping action of 65 the carrying-section, yet add materially to the strength of said carrying-section.

At each end of the carrying-section B of the

vehicle body or rack two horizontal lengths of chain 35 and 35^a are secured at one of their ends to the end portions of the side gates 25, 70 as is best shown in Figs. 2 and 3, and the lengths of chain 35 and 35^a at each end of said carrying-section are connected by a spring 36 of suitable strength, which springs serve to draw the side gates from their lower 75 or dumping position to their upper or closed position and retain such side gates in such position when used in connection with elbow-levers 38 and 38^a, pivoted one at each side of the center at each end of the carrying-section, 80 and the upright members of the elbow-levers 38 and 38^a normally engage with the outer surfaces of buttons 37, located on or formed integral with the lengths of chain 35 and 35^a, where they connect with the springs 36, the 85 upper ends of the said elbow-levers 38 and 38^a being downwardly and outwardly beveled.

Each elbow-lever 38 is pivotally connected with the upper end of a link 39, while the elbow-levers 38^a are similarly connected 90 with links 39^a. These links at their lower portions cross each other at the ends of the body or rack and are pivotally attached to the end transverse beams 12 of the base-section A at each side of the center of such beams, 95 as is shown also in Figs. 2 and 3.

When the carrying-section B of the body or rack is in its horizontal or normal position, (shown in Figs. 1 and 2,) it is supported in such position by means of the supporting-bars 19, 100 which are then perpendicular, as is shown in Fig. 1, and are in engagement with the under faces of wear-plates 40, secured to the under surface of the bottom of the carrying-sections B, the said wear-plates being provided with 105 suitable longitudinal guide-ribs 40^a, although these ribs may be omitted, if desired. When the load is to be dumped, the lever 22 at that side at which the dumping is to be accomplished is drawn downward, as is shown in Fig. 110 5, thus carrying the supporting-bars 19 at said side to the inclined position, (shown in Fig. 5,) whereupon the weight of the material in the carrying-section B will tend toward the unsupported side of the carrying-section, causing 115 said side to assume a downwardly-inclined position, (shown in Figs. 3 and 4,) and likewise cause one of the elbow-levers—the elbow-lever 38^a, for example, which is near the inclined side—to be carried away from the buttons 37, whereas the opposing elbow-levers 38 will be drawn in direction of the inclined side, whereby the elbow-levers 38^a permit the springs 36 to extend, and consequently permit the side gate at the lower side of the carrying-section to drop, while the opposing elbow-levers 38 maintain their positions at the lugs or buttons 37, adjacent to the elevated side of the carrying-section, thus holding the side gate at that side closed. This movement 125 of the elbow-levers is brought about by the movement of the links 39^a incident to the inclined position of the carrying-section A. 130 After the load has been dumped the springs

36 will again contract to close the dropped side gate, and the carrying-section of the vehicle body or rack being simply pivoted will normally assume its horizontal position, at 5 which time the pivoted supporting-bars 19 are again restored to their vertical positions.

When the carrying-section B of the body or rack is carried to its dumping position, it is held in such position until the dropped side 10 gate is elevated by means of latches 41, which are pivoted in suitable bearings 42 at the under central portions of the carrying-section B, as when the carrying-section B is inclined the latch 41 at the inclined side will engage 15 with a keeper 43 at the central upper side portion of the base-section A, one keeper 43 being at each side of the base. The latch is held in engagement with the keeper 43 while the dropped side gate is in its dropped position 20 by a beveled head 44, extending from a projecting post 45 at the outer central portion of the carrying-section B, one of the said posts being at each side of said section, and when the side gate at the lower portion of the carrying-section drops to a dumping position the head 44 of the projecting post 45 at that side of the carrying-section will extend over the pivot portion of the latch 41; but as the side gate is brought to its upper position the head 25 44 from the post 45 in action will press upon the pivoted end of the latch 41 in action and carry said latch out of engagement with its keeper 43, thereby permitting the carrying-section B to resume its horizontal or normal 30 position.

Having thus described my invention, I claim as new and desire to secure by Letters Patent—

1. A dumping carrying-section, a base-section 40 on which the carrying-section is pivotally mounted, side gates adapted to drop, and means for automatically opening one side gate and holding the other side gate closed, which means are operated through the movement of the carrying-section upon the base-section, as 45 specified.

2. In a dumping-vehicle, a carrying-section, a base-section on which the carrying-section is pivotally mounted, side drop-gates 50 for the carrying-section, a tension device normally holding the side gates closed, and means acting in conjunction with the tension device and operated by the rocking movement of the carrying-section, which tension device 55 in the normal position of the carrying-section holds both gates closed but in the tilted position of the carrying-section permits one side gate to drop, locking the opposing side gate, and automatically returns the rocked gate to 60 its closed position when the carrying-section resumes its normal position, as specified.

3. In vehicles, a base-section, a carrying-section centrally pivoted upon the base-section, drop-doors at the sides of the carrying-section, means operated by the movement of the carrying-section for controlling the drop-doors, supports for the carrying-section piv-

oted upon the base-section, and devices for raising and lowering the supports, substantially as described.

4. In vehicles, a base-section, a carrying-section centrally pivoted upon the base-section, drop-doors at the sides of the carrying-section, means operated by the movement of the carrying-section for controlling the drop-doors, supports for the carrying-section pivoted upon the base-section, devices for raising and lowering the supports, keepers upon the base-section, and latches on the carrying-section, which latches in the dumping position 70 of the carrying-section engage with the said keepers, as described.

5. In vehicles, a base-section, a carrying-section centrally pivoted upon the base-section, drop-doors at the sides of the carrying-section, means operated by the movement of the carrying-section for controlling the drop-doors, supports for the carrying-section pivoted upon the base-section, devices for raising and lowering the supports, keepers upon the base-section, latches on the carrying-section, which latches in the dumping position 85 of the carrying-section engage with the said keepers, trip devices carried by the carrying-section, which trip devices in the dumping position of the carrying-section engage with the latch in locking position, and hold the said latch in said position when a drop-door is opened, the said trip devices being adapted, when a drop-door is closed, to release the 90 latch in operation from engagement with its keeper, as described.

6. In vehicles, the combination with a base-section, a carrying-section centrally pivoted upon the base-section, doors hinged at the 105 sides of the carrying-section, chains connected with the said side doors at each end of the carrying-section, springs connecting said chains at each end of the carrying-section, and buttons located on the said chains adjacent to the terminals of the said springs, of elbow-levers pivoted on the end portions of the carrying-section, being adapted for normal engagement with the said buttons, and links pivotally connected with the elbow-levers, which links cross each other at each 110 end of the carrying-section and are pivotally connected with the end portions of the base-section, for the purpose described.

7. In vehicles, the combination with a base-section, a carrying-section centrally pivoted upon the base-section, doors hinged at the sides of the carrying-section, chains connected with the said side doors at each end of the carrying-section, springs connecting said 125 chains at each end of the carrying-section, and buttons located on the said chains adjacent to the terminals of the said springs, of elbow-levers pivoted on the end portions of the carrying-section, being adapted for normal engagement with the said buttons, links pivotally connected with the elbow-levers, which links cross each other at each end of the carrying-section and are pivotally con-

5 nected with the end portions of the base-section, keepers located upon the central side portions of the base-section, latches pivotally mounted at the central side under portions of the carrying-section, adapted for engagement with the said keepers, trip-arms carried by the side doors, adapted for engagement with the said latches, supports for the carrying-section, pivoted to the base-section, and means, 10 substantially as described, for carrying said supports to a vertical or to an inclined position, as described.

8. In vehicles, the combination with a base-section provided with a series of transverse 15 beams, bearing-blocks secured on the said beams at their centers, a carrying-section located above the base-section, side bars for the carrying-section hinged thereto, socket-blocks secured to the central portion of the base-section, 20 at its under side, pivotally connected with the said bearing-blocks, supporting-bars pivoted in longitudinal series to the base-section, links connecting the series of supporting-bars, levers connected with the said links 25 for operating the supporting-bars, and bearing-surfaces provided on the bottom portion of the carrying-section to receive the upper ends of the supporting-bars when in vertical position, of chains attached to the side doors 30 at the ends of the carrying-section, springs connecting the said chains at each end of the carrying-section, buttons located on the said chains, elbow-levers normally in engagement with the said buttons, and links pivoted to 35 the elbow-levers, which links cross each other at each end of the carrying-section and are pivotally attached to the end portions of the base-section, for the purpose set forth.

9. In a vehicle, a receptacle provided with 40 gates, tension devices connecting said gates, whereby one of said connected gates will be

held in its normal closed position, while the other is opened, substantially as set forth.

10. In a vehicle, a receptacle provided with gates, tension devices connecting said gates, 45 projections formed on said tension devices, and levers normally engaging with said projections, substantially as set forth.

11. In a dumping-vehicle, a base-section, a carrying-section mounted thereon, a gate for 50 said carrying-section, tension devices normally holding said gate in its closed position, and means actuated by the movement of the carrying-section on the base-section and acting in conjunction with the aforesaid tension 55 devices for opening said gate, substantially as set forth.

12. In vehicles, a base-section, a carrying-section mounted thereon and capable of assuming a tilted position relative to the base-section, a gate for said carrying-section, devices for supporting the carrying-sections normally horizontally, relative to the base-section, means for releasing said supporting devices, to permit the tilting of the carrying-section, tension means operated by the tilting movement of the carrying-sections, for opening the aforesaid gate, locking means for holding said gate open while the carrying-section is in its tilted position, and devices operated 70 by the return movement of the carrying-section to its horizontal position, for releasing said locking means and permitting the gate to be closed by the aforesaid tension means, substantially as set forth.

In testimony whereof I have signed my name to this specification in the presence of two subscribing witnesses.

WILLIAM L. CHESSROWN.
